UNITED STATES PATENT OFFICE.

DANIEL M. PARKINSON, OF DAYTON, OHIO.

WINDOW-SHADE BRACKET.

Application filed December 30, 1925. Serial No. 78,467.

My said invention relates to a combined window shade and curtain support and it is an object of the same to provide an improved construction of this kind which shall be simple and inexpensive to make and convenient in use.

A further object of the invention is to provide a construction of this kind by means of which lace curtains and the like can be moved out of the way in a convenient manner as to permit washing of windows.

Referring to the accompanying drawings which are made a part hereof and on which similar reference characters indicate similar parts,

Figure 1 is an elevation of my device in place on a window frame,

Figure 2, a detail of the left side of the device, with portions broken away,

Figure 3, a detail of the right side with the parts in detached relation, and

Figure 4, a plan of the device indicating a mode of operation thereof.

In the drawings reference characters 10 and 11 indicate a pair of brackets adapted to be supported near opposite sides of a window frame 12, the brackets comprising members for attachment to the right and left sides of a window frame respectively. Each member includes an upright body 13 with a forward extension 14 at the bottom, one of these extensions being formed as indicated at 15 to receive the flat projection 16 at one side of the conventional shade roller while the other has a circular orifice 17 to receive the conventional journal 18 of the shade roller. A conventional shade is indicated at 19 and the roller therefor at 20. The brackets are shown as L-shaped in section so as to provide a part lying flat against the window frame and a flange perpendicular thereto which is continuous with the extensions 14. This is indicated as being cut away at the upper end where the part lying against the frame member is widened and extended rearwardly as at 21 to provide a horizontal extension resting on an upper face of the window frame or analogous device. The extreme end of this horizontal part is here shown as provided with downwardly bent teeth 22 which engage the material of the frame to prevent accidental dislodgement of the brackets.

The brackets are perforated at 23 to receive bent arms 25 of lateral auxiliary brackets 24. Bent-up fingers 27 on the auxil-

iary brackets support the laterally extending body portions of said brackets. At their outer ends the auxiliary brackets are rolled as indicated at 28 to provide bearings for the downwardly extending fingers 29 of curtain rods 30 having rearwardly bent arms 31 connecting the body of each rod to the downwardly-bent finger. It will be seen that the curtain rods are swingable about vertical pivots in the bearings 28 whereby they can move to positions such as indicated in dotted lines at A and B in Figure 4, thus affording ready access to the window.

It will be seen from the foregoing that the brackets can be positioned on a window frame or the like and will be held securely against accidental dislodgement by means of teeth 22 or other frictional means such as will occur to those skilled in the art. When so supported they can be removed with ease without the use of tools of any character. Holes 33 are provided in the body portions 13 to receive tacks 14 for securing the bracket to the frame 12 and preventing dislodgement of the teeth 22.

It will be obvious also that the main brackets 10 and 11 can be used conveniently where only roller supported shades are to be provided for the windows. In such case the remainder of the device may be omitted or may be stored during the summer so as not to mar the appearance of the window. When lace curtains are to be hung, as in autumn, the auxiliary brackets and the curtain rods can be positioned either with or without removing the main brackets from their place and thereupon the curtains of lace or the like can be hung quickly and conveniently. Since the rods extend only to the middle of the window sash and are free at one end they can readily be moved for convenience in putting them up or taking them down or for other purposes.

It will be obvious to those skilled in the art that various changes may be made in my device without departing from the spirit of the invention and therefore I do not limit myself to what is shown in the drawings and described in the specification but only as indicated in the appended claims.

Having thus fully described my said invention, what I claim as new and desire to secure by Letters Patent is:

1. A combined curtain rod and shade holder comprising a bracket having a body adapted to be secured to a window frame in

upright position, said body having a portion extending outwardly therefrom at one side of the body and formed at its lower end for the reception of a window shade roller and provided with a slot intermediate the ends of said outwardly extending portion, an upturned finger at the opposite edge of said body and an auxiliary bracket extending through said slot and slidably resting on said upturned finger, said auxiliary bracket being formed to support a window curtain rod said rod being pivoted in its support, substantially as set forth.

2. A combined curtain rod and shade holder comprising a bracket having a substantially flat body for engagement with a window frame, said flat body having an upturned slotted portion, an auxiliary bracket adapted to lie flat against said body and fit snugly within said slotted portion for adjustable interlocking engagement with said flat body, and a curtain rod supported by said auxiliary bracket, substantially as set forth.

3. A combined curtain rod and shade holder comprising a bracket for attachment to a window frame, an upstanding element secured to said bracket and extending at substantially right angles outwardly therefrom, a supporting element on said bracket in spaced relation to said upstanding element, and auxiliary bracket adapted to rest

on said supporting element and extend through said upstanding element in substantially parallel relation to said bracket for adjustable interlocking engagement with said bracket, substantially as set forth. 35

4. A device of the class described comprising a sheet metal body having an upstanding slotted flange, a supporting element on said body in spaced relation to the slot in said flange, and a longitudinally slideable auxiliary supporting bracket extending through the slot in said flange and resting on said supporting element flat against said body, substantially as set forth. 40

5. A device of the class described comprising a sheet metal body having an upstanding slotted flange formed to support a window shade roller, a supporting element 50 on said body in spaced relation to the slot in said flange, a longitudinally slideable auxiliary supporting bracket extending through the slot in said flange and resting on said supporting element flat against said body, and a curtain rod pivoted on said auxiliary bracket and arranged to swing in a horizontal plane, substantially as set forth. 55

In witness whereof, I have hereunto set my hand at Dayton, Ohio, this 26th day of December, A. D. nineteen hundred and twenty-five. 60

DANIEL M. PARKINSON.
